BOILER CONSTRUCTION

Robert J. Needham, Toronto, Ontario, Canada,
and Howard C. Woodbridge, Rochester, N. Y.

Application June 12, 1934, Serial No. 730,280

10 Claims. (Cl. 122—4)

This invention relates to the construction of boilers, and particularly to boilers of the locomotive type, although it is applicable also to other types of boilers.

5 An object of the invention is to provide an improved boiler construction for use with mechanical stokers.

Another object is the provision of a boiler so designed and constructed that the parts of a 10 mechanical stoker projecting forwardly into the fire box are shielded or protected so that they do not burn out as they have done heretofore.

To these and other ends the invention resides in certain improvements and combinations of 15 parts, all as will be hereinafter more fully described, the novel features being pointed out in the claims at the end of the specification.

In the drawing:

Fig. 1 is a vertical section taken substantially 20 centrally through a fragment of the rear end of a boiler, showing one form of the invention;

Fig. 2 is an elevation of a fragment of the rear end of the boiler viewed from inside the fire box;

Fig. 3 is a plan of the parts shown in Fig. 2, 25 and

Fig. 4 is a vertical section similar to a part of Fig. 1, illustrating a modified form of the invention.

The same reference numerals throughout the 30 several views indicate the same parts.

In the drawing there is shown a fragment of the rear end of a boiler of the locomotive type, including the usual back head 11 and door sheet 12 which form between them the back water leg 35 of the boiler. The usual fire door opening 13 is provided, and it may be closed by a fire door, such as indicated in dotted lines at 14.

In Fig. 1 there is shown in dotted lines at 15 a diagrammatic representation of part of any 40 conventional mechanical stoker, familiar to those skilled in this art. The parts shown in dotted lines comprise, in general, means for conveying the fuel (usually coal or the like) to the fire door, and there it is placed upon a so-called distributor plate along which it is moved, in known manner, so as to be projected forwardly into the fire box.

Heretofore, these distributor plates have projected a substantial distance forwardly into the fire box, in an overhanging position so that they 50 are subjected to heat on all sides, and in service they have usually burned out rather rapidly, necessitating frequent replacement.

This burning out of the distributor plates is 55 prevented according to the present invention by providing, on the door sheet, an extension 20 pro-

jecting forwardly a material distance into the fire box at or near the lower edge of the fire door opening 13. This extension 20 has its top 21 of flat or substantially flat form providing a shelf of substantial area, approximately the full 60 width of the fire door, as shown in Fig. 2, and projecting a considerable distance forwardly into the fire box, as shown in Figs. 1 and 3. From the forward edge of the flat top 21, the sheet is bent downwardly and rearwardly on a sufficiently 65 large radius to avoid danger of cracking, and thence extends obliquely downwardly and rearwardly, as indicated at 22, at an angle diverging from the top 21, as plainly shown in Fig. 1. Then the sheet bends again downwardly at a greater 70 angle to the shelf portion 21, and merges into the normal plane of the door sheet 12, all as plainly seen in the drawing. The extension is provided with suitable stay bolts 23 so that it may withstand the boiler pressure without bulging, and it will 75 be seen that this extension is hollow and in free communication with the rest of the water leg, so that it forms in effect a part of the water leg, and the water circulates freely in the extension 80 as well as in the rest or usual part of the water leg.

Stay bolts 24 are provided, as usual, between the back head 11 and the door sheet 12, wherever required.

The top surface of the shelf 21 may itself form 85 and be used as the distributor plate of the stoker, over which the fuel moves when projected forwardly into the fire box. Suitable ribs or guides for the fuel may be formed on or attached to the top of the plate 21, if desired, as will be understood by those familiar with mechanical stokers. The distributor plate, when formed in this manner will have an exceedingly long life in comparison to prior distributor plates, because it is, 90 in effect, part of the water leg of the boiler and the metal is kept cool by reason of the circulation in the water leg, so that it does not burn out even though the shelf 20 projects a material distance into the fire box.

If desired, however, the plate 21 itself need not be used as the distributor plate, but a separate distributor plate 30, of any suitable construction, can overlie the plate 21, as shown in the alternative construction illustrated in Fig. 4. This 95 construction is equally satisfactory, because the distributor plate 30, even though it may be of more or less conventional form, is protected by the water leg extension 20, which shields it from the heat rising from below, so that the distributor 100 105 110

plate 30 is not burned out as it has been heretofore.

It will usually be most convenient to form the extension 20 from a separate plate, suitably shaped and welded or riveted to the door sheet 12, but the extension may nevertheless be considered as formed by a part of the door sheet because, from a practical standpoint, the parts 20, 21, and 22 are, in effect, part of the door sheet.

10 Throughout the foregoing description and in the accompanying claims, the term "fire door opening" is intended to refer to any opening through which fuel may be introduced into the fire box, whether such opening be commonly referred to as a fire door opening or by any other name.

We claim:

1. A boiler for use with a mechanical stoker, comprising a back head and a door sheet forming between them a water leg and provided with a fire door opening, and a hollow extension on said door sheet projecting forwardly substantially at the bottom of said fire door opening to form a shelf extending a material distance into the fire box, the interior of said extension being in communication with said water leg.

2. A boiler for use with a mechanical stoker, comprising a back head and a door sheet forming between them a water leg and provided with a fire door opening, said door sheet being formed to provide, adjacent the bottom of said fire door opening, an overhanging shelf of a width approximating that of said fire door opening and a length projecting a material distance forwardly into the fire box.

3. A boiler for use with a mechanical stoker, comprising a back head and a door sheet forming between them a water leg and provided with a fire door opening, said door sheet being formed to provide, adjacent the bottom of said fire door opening, an overhanging shelf having a substantially flat top extending forwardly a material distance into the fire box.

4. A boiler for use with a mechanical stoker, comprising a back head and a door sheet forming between them a water leg and provided with a fire door opening, said door sheet being formed to have a substantially flat portion extending forwardly a material distance into the fire box near the bottom of said fire door opening, said door sheet thence extending downwardly and obliquely rearwardly at an angle diverging from said flat portion thereof, and thence downwardly at a sharper angle substantially parallel to said back head.

5. A boiler comprising a back head and a door sheet forming between them a water leg and provided with a fire door opening, and stoker distributor plate means including an extension formed on said door sheet providing a hollow overhanging shelf projecting a material dis-

tance forwardly into the fire box near the bottom of said fire door opening, the interior of said hollow shelf forming a part of said water leg and being in free communication with the rest of said water leg.

6. A boiler comprising a back head and a door sheet forming between them a water leg and provided with a fire door opening, and an extension formed on said door sheet providing a hollow overhanging shelf projecting a material distance forwardly into the fire box near the bottom of said fire door opening, the interior of said hollow shelf forming a part of said water leg and being in free communication with the rest of said water leg, and the top surface of said hollow shelf forming a distributor plate for a mechanical stoker.

7. A boiler comprising a back head and a door sheet forming between them a water leg and provided with a fire door opening, an extension formed on said door sheet providing a hollow overhanging shelf projecting a material distance forwardly into the fire box near the bottom of said fire door opening, the interior of said hollow shelf forming a part of said water leg and being in free communication with the rest of said water leg, and a stoker distributor plate overlying said shelf and protected thereby from heat rising from below it.

8. A boiler fire box comprising two sheets forming between them a water leg having an opening therethrough, and a hollow extension on one of said sheets substantially at the bottom of said opening to form a shelf projecting a material distance into the fire box, the interior of said extension being in communication with said water leg.

9. A boiler fire box comprising two sheets forming between them a water leg having an opening therethrough, and a hollow extension on one of said sheets providing a hollow overhanging shelf projecting a material distance into the fire box near the bottom of said opening, the interior of said hollow shelf forming a part of said water leg and being in free communication with the rest of said water leg, and the top surface of said hollow shelf forming a distributor plate for a mechanical stoker.

10. A boiler fire box comprising two sheets forming between them a water leg having an opening therethrough, a hollow extension on one of said sheets providing a hollow overhanging shelf projecting a material distance into the fire box near the bottom of said opening, the interior of said hollow shelf forming a part of said water leg and being in free communication with the rest of said water leg, and a stoker distributor plate overlying said shelf and protected thereby from heat rising from below it.
